GEORGE B. EMERSON AND CHARLES E. BUYSSE, OF DETROIT, MICHIGAN.

MIXING-VALVE.

1,323,526.

Specification of Letters Patent.

Patented Dec. 2, 1919.

Application filed September 16, 1916. Serial No. 120,532.

To all whom it may concern:

Be it known that we, GEORGE B. EMERSON and CHARLES E. BUYSSE, citizens of the United States, residing at Detroit, county 5 of Wayne, State of Michigan, have invented a certain new and useful Improvement in Mixing-Valves, and declare the following to be a full, clear, and exact description of the same, such as will enable others skilled 10 in the art to which it pertains to make and use the same, reference being had to the accompanying drawings, which form a part of this specification.

Our invention relates to mixing valves 15 and an object of our improvements is to provide a valve of an improved construction for mixing gas and air to form a combustible mixture.

We secure this object in the device illustrated in the accompanying drawings in 20 which,

Figure 1 is a sectional elevation of a valve embodying our invention.

Fig. 2 is a plan view, a part being broken 25 away on the line B—B—B Fig. 1.

Fig. 3 is an elevation principally in section on the line C—C Fig. 1, looking from the right of the latter figure.

Fig. 4 is a diagrammatic view illustrating 30 the connections of the valve embodying our invention.

a is the casing. This is provided with a gas inlet passage *b* and an air passage *c*. This latter is connected by a pipe *y* (Fig. 4) 35 to the source of air pressure illustrated as a blower *z*. *d* is the delivery passage. This is connected with the pipe *x* by which the mixture of gas and air is conveyed to the point of combustion.

40 The casing *a* is provided with a cylindrical bore in which fits and rotates and slides axially a plug *e*. There is a port *a*² opening through the wall of the casing *a* and into the gas passage *b*. There is a port *a*³ opening through the wall of the casing *a* 45 opposite the port *a*² and communicating with the air passage *c*. The passage through the casing *a* is contracted at *d*² to form a choke, or venturi, portion.

50 The plug *e* is provided with two upwardly extending guide pieces *e*² *e*³. *a*⁴ is an annular shoulder formed at the upper end of the vertical bore of the casing *a* and on this shoulder fits a closing disk *f*. *j* is a retaining ring which is secured to the upper end 55 of the casing *a* and holds the disk *f* in place.

The guide pieces *e*² *e*³ pass through apertures in the disk *f* and are guided thereby. *e*⁵ is a cylindrical rod extending axially upward from the plug *e* and passing through a 60 cylindrical aperture in the disk *f*. *g* is a nut, having a milled end-disk *g*², the threads of which engage the protruding upper end of the rod *e*⁵. *i* is a spring pressing at one end against the disk *f* and at the other 65 against the plug *e*. By turning the nut *g* the position of the plug *e* may be adjusted axially in the bore of the casing *a*. *f*³ is a handle by which the disk *f* may be rotated carrying with it the plug *e*. 70

The plug *e* is hollow and through its wall are formed ports *e*³ *e*⁴ adapted, respectively, to register with the ports *a*² *a*³ in the casing *a*. The ports *a*³ *e*⁴ and *a*² *e*³ are so located that when the plug *e* is adjusted axially in 75 the casing *a* one of the ports in the plug will increase its area of opening with reference to the corresponding port in the casing *a* and the other will decrease its opening with its corresponding port. 80

*e*⁵ is a conduit formed integral with the plug *e* communicating with the port *e*⁴ at one end, extending inward and downward coaxially with the plug *e*, and opening at the lower end at or just beyond the venturi contraction *d*² of the bore of the casing *a*. *e*⁶ is a reducing plug in the end of the conduit *e*⁵, which may be used when it is desired to increase the velocity of the jet. 85

The operation of the above described device is as follows:

By manipulating the nut *g*, the axial position of the plug *e* in the bore of the casing *a* is adjusted so that the registering areas of the ports *e*³ *a*² and *a*³ *e*⁴ are adjusted to get 95 the proper proportion of gas and air. Inasmuch as one area increases and the other decreases when the plug *e* is moved axially in the casing *a*, this proportion may be easily adjusted. The plug *e* is then rotated by 100 means of the handle *f*³ to give the desired quantity of air and gas mixture, the rotation of the plug *e* varying the quantities of gas and air in the same proportion.

The air being forced through the conduit *e*⁵ acts to suck the gas from the pipe *b*. 105

What we claim is:

1. The combination of a valve casing having a lateral opening in its wall communicating with a source of fuel gas, and a lateral 110 opening through its wall communicating with a source of air supply, a plug adapted

to rotate and slide axially in said casing, said plug having two passages adapted to deliver currents of gas in the same direction, a lateral opening in said plug communicating with one of said delivery passages and adapted to register with one of the apertures in the wall of said casing, a lateral opening in said plug communicating with the other of said delivery passages and adapted to register with the other of said apertures through the wall of the valve casing, and means for reciprocating and rotating said plug, the lateral openings in said plug being so arranged with reference to the apertures through the wall of said casing that the registering area of one of said openings to the corresponding aperture in the casing shall increase and the registering area of the other opening and aperture shall diminish when the plug is adjusted axially in said casing.

2. The combination of a valve casing having a lateral opening in its wall communicating with a source of fuel gas, and a lateral opening through its wall communicating with a source of air supply, a plug adapted to rotate and slide axially in said casing, said plug having two passages adapted to deliver currents of gas in the same direction, a lateral opening in said plug communicating with one of said delivery passages and adapted to register with one of the apertures in the wall of said casing, a lateral opening in said plug communicating with the other of said delivery passages and adapted to register with the other of said apertures through the wall of the valve casing, and means for reciprocating and rotating said plug, the lateral openings in said plug being so arranged with reference to the apertures through the wall of said casing that the registering area of one of said openings to the corresponding aperture in the casing shall increase and the registering area of the other opening and aperture shall diminish when the plug is adjusted axially in said casing, and means for

forcing air toward the casing in the air supply passage, said delivery passages being so arranged that the discharge of air from one of said passages shall decrease the pressure at the discharge end of the other of said passages.

3. A mixing valve comprising a valve casing having a valve chamber provided with an air and a gas port and with an outlet through which the air and gas mixture is adapted to be drawn, a valve in the casing having ports adapted to register respectively with the air and gas ports in the casing to communicate the latter ports with the outlet opening, said ports being so arranged that by adjustment of the valve the effective area of both the air and gas ports may be correspondingly increased or diminished and also the effective area of the air port may be increased and of the gas port diminished, and vice versa, means for adjusting the valve to correspondingly adjust both air and gas ports, and means for inversely adjusting said ports.

4. A mixing valve comprising a casing having a cylindrical valve chamber provided with a plurality of intake ports and an outlet, a cylindrical valve adapted to be oscillated and adjusted longitudinally in the valve chamber, the valve having a plurality of ports adapted to register with said intake ports to communicate the same with the outlet in the casing, the ports being so arranged that upon oscillating the valve the effective areas of the several registering ports may be correspondingly varied and upon adjustment of the valve longitudinally the effective area of one of the ports will be increased and the other diminished, and vice versa, and means for oscillating the valve and adjusting it longitudinally.

In testimony whereof, we sign this specification.

GEORGE B. EMERSON.
CHARLES E. BUYSSE.
